CLAIM

The ornamental design for a folding background support bracket, as shown and described.

DESCRIPTION

FIG. 1 is a front perspective view of a folding background support bracket showing my new design;

FIG. 2 is a front elevation view thereof;

FIG. 3 is a back elevation view thereof;

FIG. 4 is a left side view thereof;

FIG. 5 is a right side elevation view thereof;

FIG. 6 is a top plan view thereof;

FIG. 7 is a bottom plan view thereof;

FIG. 8 is a back elevation view thereof, shown in condition of use with a backdrop disclosed in broken lines to illustrate an environment; and,

FIG. 9 is a disassembled view of the folding background support bracket which is shown in a folded configuration. The broken lines in the drawings depict portions of the folding background support bracket that form no part of the claimed design. The broken lines showing a backdrop in FIG. 8 represent environmental structure and form no part of the claimed design.
